UNITED STATES PATENT OFFICE.

EDGAR H. WILSON, OF CHARTIERS TOWNSHIP, ALLEGHENY COUNTY, PENNSYLVANIA,
ASSIGNOR TO TAYLOR-WILSON MANUFACTURING COMPANY, OF MCKEES ROCKS,
PENNSYLVANIA, A CORPORATION OF PENNSYLVANIA.

PIPE CUTTING, ROUNDING, AND THREADING MACHINE.

Application filed June 7, 1920, Serial No. 387,246. Renewed May 4, 1922. Serial No. 558,425.

To all whom it may concern:

Be it known that I, EDGAR H. WILSON, a citizen of the United States, residing at Chartiers Township, Allegheny County,

5 Pennsylvania, have invented a new and useful Improvement in Pipe Cutting, Rounding, and Threading Machines, of which the following is a full, clear, and exact description.

10 The present invention relates broadly to machines for cutting off and threading lengths of material and more particularly to a machine of this character for cutting off, rounding and threading lengths of pipe.

15 The principal object of the present invention is to provide a machine of this character, having means for positively advancing the threading die, whereby the threads may be more accurately chased by the use of 20 less power, and without receiving any strains tending to strip the same.

A further object of the present invention is to provide a plurality of independently 25 operable means for moving the threading die, which means may be individually employed at will.

Still a further object of the invention is to provide means for rotating the material being operated upon at different speeds, 30 which speeds are under the control of the operator.

An additional object of the present invention is to provide means for rounding the material being operated upon, the 35 rounding means being controllable for exerting different pressures on the material.

The foregoing and other objects, together with their attendant advantages, will be apparent as the invention becomes better understood, by reference to the accompanying specification and drawings forming a part thereof, it being premised that changes may be made in the various details and the manner of operation, within the scope of the appended claims, without departing from the spirit of the invention.

Figure 1 is a side view of a machine built in accordance with the present invention;

50 Figure 2 is a longitudinal section partly in elevation of the machine illustrated in Figure 1;

Figure 3 is an end view of the front of the machine;

Figure 4 is an end view of the rear of the machine;

55 Figure 5 is a detail view of one of the clamps;

Figure 6 is a sectional view through one of the clamps;

60 Figure 7 is an enlarged detail view partly in section of a portion of the cut-off mechanism;

Figure 8 is a side elevation, on an enlarged scale, of the adjusting and operating means for the rounding device;

65 Figure 9 is an enlarged sectional view through the clamping nut for connecting the lead screw to the movable carriage; and

Figure 10 is a diagrammatic view of the change speed gearing for the lead screw.

70 At the present time it is customary to drive machines for cutting, threading and rounding pipe, at a substantially constant speed. It is highly advantageous, however, to vary this speed in accordance with the 75 diameter of the material being operated upon and in accordance with the character of work being performed thereon. At the present time it is also customary to thread the material by means of a threading die 80 mounted in a carriage, which carriage is advanced by the thread being chased. This load imposed on the thread frequently results in stripping the same. The present 85 invention provides a variable speed drive and means for positively advancing the carriage carrying the threading die.

Referring more particularly to the drawings, there is illustrated a machine comprising a frame 1, having projecting from one 90 end thereof a base 2 adapted to slidably support the carriage 3. Extending longitudinally through the frame 1 is a barrel 4 having formed on its front end a casing 5 adapted to receive a series of radially adjustable gripping jaws 6. These jaws are mounted as is customary in machines of this general nature for adjustment by means of screws 7, accessible through openings 8 formed in the casing 5. Each of the jaws 6 is also mounted in a block 9, which is adapted to be adjusted radially independently of the adjustment just described. This second adjustment is secured by means of levers 10 having pivotal mountings 11 on the 100 barrel 4 and bifurcated at their front ends.

to enter openings 12 formed in the blocks 9 on opposite sides of the adjustable jaws 6. The rear ends of the levers 10 may each be provided with a roller 13 adapted to cooperate with a cam surface 14 formed on a sliding sleeve 15. For sliding this sleeve longitudinally of the barrel 4, it is provided with a groove in which is mounted a collar 16 operatively connected to the arms 17 of an operating yoke mounted on the transversely extending shaft 18. Operatively connected to one end of the shaft 18, is an arm 19 having a link connection 20 with a similar arm 21 on the transversely extending shaft 22. This shaft 22 may be provided with an operating lever 23, as indicated in chain lines in Figure 1, or it may be extended through the frame of the machine and connected at its opposite end by means of an arm 24 with the piston rod 25 of a piston operable in the air cylinder 26. In some instances, both the air cylinder and the lever 23 may be simultaneously employed, thereby providing independent means for rocking the shaft 18 and sliding the sleeve 15 on the barrel for opening or closing the jaws 6. According to the illustrated embodiment of the invention there are three of these jaws provided for simultaneous operation in the manner described.

As soon as the pipe, or other material to be operated upon, has been placed in the barrel 4 and gripped therein, the barrel is rotated. This rotation is accomplished by means of a motor 27 which is preferably a variable speed motor. If of the direct current type, this motor may have its speed controlled by a suitable field rheostat. I may, however, employ a multi-speed alternating current induction motor of the well known type. The armature or driving shaft 28 of this motor may be provided with a gear 29 meshing with a gear 30 on the shaft 31. The gear 30 in turn meshes with a similar gear 32 loosely carried on the shaft 33. The shaft 31 also carries a second gear 34, meshing with a similar gear 35 loosely carried on the shaft 33. Intermediate the gears 32 and 35 there may be mounted a clutch for establishing an operative driving connection between either of these gears and the shaft. By operating the clutch in the desired direction, the required speed of rotation of the shaft 33 may be produced. This rotational movement is transmitted from the shaft 33 to the barrel by means of a gear 36 meshing with the ring gear 37 keyed to a hub 38, which is in turn keyed to the barrel 4. By utilizing a variable speed motor in combination with a change speed gear, it will be apparent that any one of a large number of different speeds of rotation may be imparted to the barrel. This feature is highly important, as it enables the operator to regulate the speed as required.

The motor 27, in the preferred embodiment of my invention, is also utilized for moving the carriage 3. This driving movement of the carriage is preferably produced through either of a series of independent mechanisms, whereby different speeds of movement may be obtained. One of these mechanisms comprises a gear 39, mounted on the barrel 4, and meshing with a gear 40 on the stub shaft 41, adapted to drive the shaft 42 by means of the gears 43 and 43'. The shaft 42 is provided with a longitudinally extending key-way in co-operative engagement with which slides a pinion 44 mounted between the arms 45 of an operating handle 46, and meshing with a pinion 47, adapted to be moved by means of the handle into engagement with any one of the change speed gears 48. The gears 48 are mounted on one end of the lead screw 49, thereby enabling the speed of rotation of the lead screw to be varied as desired.

Extending transversely of the carriage 3, and mounted in suitable bearings 50 thereon, is a rod 51 provided on one end with an operating handle 52. Intermediate its ends the rod is provided with a rack 53 adapted to mesh with pinions 54 rotatable in bearings in the carriage 3. These pinions are each provided with diametrically opposite cam slots 55 for the reception of pins 56 projecting from the sides of the two halves 57 of a lead screw nut surrounding the lead screw. By sliding the rod 51 transversely, the pinions 54 will be rotated to clamp the two halves of the lead screw nut around the lead screw. When this engagement has been made, it will establish an operative driving connection between the lead screw and the carriage 3, thereby positively driving the carriage by the lead screw.

A second means for moving the carriage 3 more rapidly than the movement which can be produced by the lead screw is also provided. This means in the illustrated embodiment of the invention comprises a sprocket wheel 58 surrounding the barrel 4 and keyed thereto for driving a sprocket chain 59 passing around a suitable wheel 60 on one end of the shaft 61. The shaft 61 extends parallel to a second shaft 62 in the base 2 and is adapted to drive the same in a forward direction by means of the gears 63 or in a reverse direction by means of the gears 64. For controlling the direction of rotation of the shaft 62, there is provided a double cone clutch 65, either portion of which may be brought into operation by an arm 66 connected to the internal cone members. The arm 66 is formed with an internally threaded opening co-operating with the threaded portion 67 of the shaft 68 extending longitudinally of the base 2. This shaft is provided with a spiral gear 69 adapted to mesh with a second spiral gear 130

70 on the rod 51. When the rod 51 is moved laterally as described, to establish an operative driving connection between the lead screw nut and the lead screw, the operating 5 handle 52 will pass between the forks 71. When in this position the rod 51 cannot be rotated. With the rod 51 in its normal position, however, it may be rotated to establish an operative driving connection between one 10 of the cone clutches 65 and the shaft 62. When such a connection is established, the shaft 62 will drive the shaft 72 by means of the bevel gears 73. As the shaft 72 is provided with pinions 74, meshing with the 15 racks 75 on the carriage 3, it will be apparent that the carriage may be rapidly moved in either direction. In actual operation the rack and pinion mechanism will be employed for obtaining quick movements of 20 the carriage, while the lead screw will be utilized for obtaining the slow movements necessary for chasing threads. It will be apparent that the lead screw may be made removable if desired, so that new lead screws 25 having different pitches corresponding to the pitches of the threads being chased, may be substituted.

The carriage 3 is formed with an opening 76, on the opposite sides of which are guides 30 77. Between the guides 77 is mounted a removable rounding block 78 adapted to co-operate with the under side of the pipe as it rotates. A second block 79 is also mounted between the guides 77 and is secured to a 35 cross-head 80, by means of which it may be raised and lowered. Secured to the cross-head 80 is a link 81 forming one portion of a toggle joint and having its free end pivotally connected by pivot 82 to a second link 83. The link 83 has a pivotal mounting 84 on the block 85, which block may be vertically adjusted by means of the screw 86 for varying the amount of movement imparted to the crosshead 80 and thereby increasing or decreasing the pressure exerted on the 45 pipe by the blocks 78 and 79. For operating the toggle links, the pin 82 is extended through a slot 87 in the piston rod 88, this rod being moved in opposite directions by cylinders 89 which may be supplied with fluid pressure at the will of the operator.

The carriage 3 also has a guide-way extending transversely therethrough for the reception of a cutting tool holder 90 provided with a cutting off tool 91. The holder is adapted to be reciprocated to move the cutter into and out of engagement with the pipe by means of a rack 92 formed thereon and meshing with a pinion 93 on the shaft 94. The rotation of the shaft is controlled by means of a handle 95 under the control of the operator. By means of this mechanism the cutting off tool may be rapidly moved to the required position. This feature is highly advantageous, as machines

of this nature are adapted to operate on materials having wide differences in diameters.

To the back of the carriage is secured a vertical pintle 96 forming a pivotal mounting for the gate 97, in which are mounted 70 advancing and receding thread chasers of any well known construction. These chasers may be moved into operative engagement with the pipe after the same has been rounded by the mechanism described by means of 75 a handle lever 98, and the gate may be held in its operative position by a suitable latch 99.

The term "barrel" as used throughout the specification and claims, is used in its broadest sense as defining any hollow structure capable of receiving therethrough or gripping the material being operated upon.

The construction relating to the rounding mechanism disclosed herein is made the subject matter of my divisional application 85 Serial No. 558,227, filed May 3, 1922.

The advantages of the present invention arise from the regulable driving means provided for the barrel and also from the independent means provided for positively moving the carriage.

Further advantages arise from the means provided for exerting a variable pressure on the rounding blocks whereby light gauge or 95 heavy gauge material may be shaped.

I claim:

1. In a machine of the class described, a barrel, means co-operating therewith for gripping the material being operated 100 upon, means for rotating said barrel, a movable threading die, and a plurality of independently operable means driven by said barrel, rotating means for positively advancing said die, one of said means being effective for also retracting said die, substantially as described.

2. In a machine of the class described, a rotatable barrel, means co-operating therewith for gripping the material being operated upon, means for rotating said barrel, a movable threading die, means for advancing said die, independent means for positively advancing and retracting said die, and means for establishing an operative driving 115 connection between said barrel rotating means and said advancing or advancing and retracting means, substantially as described.

3. In a machine for cutting and rounding pipe, a rotatable barrel adapted to receive 120 the pipe, means for rotating said barrel, a carriage, a cutting mechanism carried thereby, means for operating said mechanism, a rounding device on said carriage, means for exerting a variable pressure on said rounding device, and mechanical means for moving said rounding device into and out of operative position, substantially as described.

4. In a pipe cutting, rounding and threading machine, a rotatable barrel adapted to 130

- receive the pipe, means for rotating said barrel, a carriage, a cutting mechanism carried thereby, a threading die on said carriage, a rounding device on said carriage, means for exerting a variable pressure on said rounding device, and mechanical means for moving said rounding device into and out of operative position, substantially as described. 5. In a machine for rounding and threading pipe, a rotatable barrel for receiving the pipe, means for rotating said barrel, a carriage, a threading die on said carriage, a rounding device on said carriage, means for exerting a variable pressure on said rounding device, and mechanical means for moving said rounding device into and out of operative position, substantially as described. 6. In a machine for cutting, threading and rounding pipe, a rotatable barrel for receiving the pipe, means for rotating said barrel at variable speeds, a carriage, a cutting device, a threading die and a rounding device on said carriage, and means for positively moving said carriage by said barrel rotating means, substantially as described. 7. In a machine for cutting and rounding pipe, a rotatable barrel adapted to receive the pipe, means for rotating said barrel, a carriage, a cutting mechanism carried thereby, means for operating said mechanism, a rounding device on said carriage, means for exerting a variable pressure on said rounding device and means for positively moving said carriage by said barrel rotating means, substantially as described. 8. In a pipe cutting, rounding and threading machine, a rotatable barrel adapted to receive the pipe, means for rotating said barrel, a carriage, a cutting mechanism carried thereby, a threading die on said carriage, a rounding device on said carriage, means for exerting a variable pressure on said rounding device, and means for positively moving said carriage by said barrel rotating means, substantially as described. 9. In a machine for rounding and threading pipe, a rotatable barrel for receiving the pipe, means for rotating said barrel, a carriage, a threading die on said carriage, a rounding device on said carriage, means for exerting a variable pressure on said rounding device and means for positively moving said carriage by said barrel rotating means, substantially as described. 10. In a machine for cutting and rounding pipe, a rotatable barrel adapted to receive the pipe, means for rotating said barrel, a carriage, a cutting mechanism carried thereby, means for operating said mechanism, a rounding device on said carriage, means for exerting a variable pressure on said rounding device and means for positively moving said carriage by said barrel rotating means, substantially as described. 11. In a pipe cutting, rounding and threading machine, a rotatable barrel adapted to receive the pipe, means for rotating said barrel, a carriage, a cutting mechanism carried thereby, a threading die on said carriage, a rounding device on said carriage, means for positively moving said carriage by said barrel rotating means, substantially as described. 12. In a machine for rounding and threading pipe, a rotatable barrel for receiving the pipe, means for rotating said barrel, a carriage, a threading die on said carriage, a rounding device on said carriage, and means for positively moving said carriage by said barrel rotating means, substantially as described. 13. In a machine for cutting and rounding pipe, a rotatable barrel adapted to receive the pipe, means for rotating said barrel, a carriage, a cutting mechanism carried thereby, means for operating said mechanism, a rounding device on said carriage, means for positively moving said carriage in either direction by said barrel rotating means, and means independent of said last named means for positively advancing said carriage, substantially as described. 14. In a pipe cutting, rounding and threading machine, a rotatable barrel adapted to receive the pipe, means for rotating said barrel, a carriage, a cutting mechanism carried thereby, a threading die on said carriage, a rounding device on said carriage, means for positively moving said carriage in either direction by said barrel rotating means, and means independent of said last named means for positively advancing said carriage, substantially as described. 15. In a machine for rounding and threading pipe, a rotatable barrel for receiving the pipe, means for rotating said barrel, a carriage, a threading die on said carriage, a rounding device on said carriage, means for positively moving said carriage in either direction by said barrel rotating means, and means independent of said last named means for positively advancing said carriage, substantially as described. 16. In a machine for cutting and rounding pipe, means for gripping and rotating the pipe, a carriage, a cutting mechanism carried thereby, means for operating said mechanism, a rounding device on said carriage, means for exerting a variable pressure on said rounding device, and mechanical means for positively moving said carriage, substantially as described. 17. In a machine for cutting and rounding pipe, means for gripping and rotating the pipe, a carriage, a cutting mechanism carried thereby, means for operating said mechanism, a rounding device on said carriage, means for exerting a variable pressure on said rounding device, and a plurality of

independently operable power-operated means for positively moving said carriage, substantially as described.

18. In a pipe cutting, rounding and threading machine, means for gripping and rotating the pipe, a carriage, a cutting mechanism carried thereby, a threading die on said carriage, a rounding device on said carriage, means for exerting a variable pressure on said rounding device, and mechanical means for positively moving said carriage, substantially as described.

19. In a pipe cutting, rounding and threading machine, means for gripping and rotating the pipe, a carriage, a cutting mechanism carried thereby, a threading die on said carriage, a rounding device on said carriage, means for exerting a variable pressure on said rounding device, and a plurality of independently operable power-operated means for moving said carriage, substantially as described.

20. In a machine for rounding and threading pipe, means for gripping and rotating the pipe, a carriage, a threading die on said carriage, a rounding device on said carriage, means for exerting a variable pressure on said rounding device and mechanical means for positively moving said carriage, substantially as described.

21. In a machine for rounding and threading pipe, means for gripping and rotating the pipe, a carriage, a threading die on said carriage, a rounding device on said carriage, means for exerting a variable pressure on said rounding device, and a plurality of independently operable power-operated means for positively moving said carriage, substantially as described.

22. In a machine for cutting and rounding pipe, means for gripping and rotating the pipe, a carriage, a cutting mechanism carried thereby, means for operating said mechanism, a rounding device on said carriage, and mechanical means for positively moving said carriage, substantially as described.

23. In a machine for cutting and round-

ing pipe, means for gripping and rotating the pipe, a carriage, a cutting mechanism carried thereby, means for operating said mechanism, a rounding device on said carriage, and a plurality of independently operable power-operated means for moving said carriage, substantially as described. 50 55

24. In a pipe cutting, rounding and threading machine, means for gripping and rotating the pipe, a carriage, a cutting mechanism carried thereby, a threading die on said carriage, a rounding device on said carriage, and mechanical means for positively moving said carriage, substantially as described. 60

25. In a pipe cutting, rounding and threading machine, means for gripping and rotating the pipe, a carriage, a cutting mechanism carried thereby, a threading die on said carriage, a rounding device on said carriage, and a plurality of independently operable power-operated means for positively moving said carriage, substantially as described. 65 70

26. In a pipe cutting, rounding and threading machine, means for rotating the pipe, a carriage, a cutting mechanism carried thereby, a threading die on said carriage, a rounding device on said carriage, power-operated means for positively moving said carriage in either direction and power-operated means independent of said last named means for positively moving said carriage in one direction, substantially as described. 75 80

27. In a machine for rounding and threading pipe, means for rotating the pipe, a carriage, a threading die on said carriage, a rounding device on said carriage, power-operated means for positively moving said carriage in either direction and power-operated means independent of said last named means for positively moving said carriage in one direction, substantially as described. 85 90

In testimony whereof, I have hereunto set my hand.

EDGAR H. WILSON.
